Primary Examiner — Karen E Eldridge Powers

(57) **CLAIM**

The ornamental design for a brush, as shown and described.

DESCRIPTION

FIG. 1 is a top, front, left side perspective view of a brush showing my new design;

FIG. 2 is a bottom, rear, right side perspective view thereof;

FIG. 3 is a front elevation view thereof, the rear elevation view being a mirror image of the front elevation view;

FIG. 4 is a left side elevation view thereof, the right side elevation view being a mirror image of the left side elevation view;

FIG. 5 is an enlarged top plan view thereof; and,

FIG. 6 is an enlarged bottom plan view thereof.

1 Claim, 4 Drawing Sheets
